[57] CLAIM

The ornamental design for a front luggage panel, as shown and described.

DESCRIPTION

FIG. 1 is a perspective view taken from the top, front, left side of a front luggage panel embodying my new design; FIG. 2 is a top plan view thereof; FIG. 3 is a front view thereof; FIG. 4 is a right side view thereof; FIG. 5 is a left side view thereof; and, FIG. 6 is a bottom view thereof.

The broken lines represent stitch lines. The broken lines showing of luggage is for illustrative purpose only and forms no part of the claimed design.
